UNITED STATES PATENT OFFICE.

CLEN S. HUMPHREY, OF BROOKLYN, NEW YORK.

BOX-OPENING DEVICE.

Application filed February 6, 1922. Serial No. 534,559.

To all whom it may concern:

Be it known that I, CLEN S. HUMPHREY, a citizen of the United States, and a resident of the city of New York, borough of Brooklyn, in the county of Kings and State of New York, have invented a new and Improved Box-Opening Device, of which the following is a full, clear, and exact description.

10 This invention relates to box opening devices and refers more particularly to an improvement over a similar device covered by Letters Patent of the United States, No. 1,334,245, issued March 16, 1920.

15 Heretofore it has been the common practice to rivet opening devices to either the box body or lid, which necessitates the forming of a perforation or aperture therein to receive the rivet. This practice very often 20 destroys the air-tight protection to the contents of the box and permits the evaporation or other deterioration of the same.

25 The present invention contemplates a means of attachment for the opening device which eliminates the necessity of perforating or otherwise forming the cover or body with an aperture.

30 Furthermore the means of attachment which consists in forming a plait or fold in the cover which receives one extremity of the opening device, provides the cover with an annular bead with which the fingers may 35 coact for more readily effecting the entire removal of the cover after the opening device has been operated to cause a partial separation of the cover from the box body.

35 With the above recited and other objects in view, the invention resides in the novel construction set forth in the following specification, particularly pointed out in the appended claims and illustrated in the accompanying drawings, it being understood that the right is reserved to embodiments other than those actually illustrated herein to the 45 full extent indicated by the general meaning of the terms in which the claims are expressed.

In the drawings—

0 Figure 1 is a plan view of a box constructed in accordance with the invention.

Fig. 2 is a side elevation thereof.

Fig. 3 is a fragmentary enlarged sectional view illustrating in dotted lines the operation of the opening device.

Referring to the drawings by characters of reference, 10 designates a box body pro-

vided at its lower edge with a bead 11 at the juncture of the side wall with the bottom thereof and an intermediate circumferential bead 12 in the side wall with which the lower 60 edge of the flange 13 of the cover 14 coacts to limit the telescopic movement of the cover over the body. The opening device illustrated in the present application and set forth in the prior patent heretofore noted 65 consists of a normally arcuate resilient finger 15 attached at one extremity to the cover 14 and engaged at its free extremity with the bead 11 of the box body, said finger being attached in such a manner as to prevent 70 lateral swinging movement with respect to the box.

In the prior patent the means for attaching the finger to the cover consists in the employment of rivets or a single rivet and 75 beads or upstruck portions, which construction tended to destroy the air-tight enclosure of the contents. In the present application the means of attaching the finger to the box 80 cover consists of an expanded annular plait or fold 16 formed substantially at the juncture of the flange 13 with the cover between which the upper end of the finger 15 is received and clamped. Under this arrangement the employment of a rivet or other 85 fastening means which necessitates aperturing or perforating the cover is eliminated and the air-tight enclosure of the contents is insured. The fold or plait 16 in addition to providing a means of attachment produces 90 on the cover 14 a peripheral bead or projection 17 with which the fingers of the operator may coact to remove the cover after the initial partial separation of the same 95 from the body has been effected by the opening device. To effect the initial partial separation of the opening device, the operator presses inwardly on the finger 15 thereby tending to strengthen the same as illustrated in dotted lines in Fig. 3. It follows that 100 the cover is partially separated at one side from the box body as will be clearly understood from the drawings.

I claim:

1. In a box and opening device therefor of 105 the character described, means for attaching said opening device comprising an annular expanded plait or fold between which one extremity of the opening device is received and clamped.

2. In a box and opening device therefor of the character described, means for at-

taching said opening device comprising an annular expanded plait or fold between which one extremity of the opening device is received and clamped, said annular plait or fold providing a manipulating bead for removing the cover.

3. In a box including a body having a bead thereon, a cover having a peripheral expanded plait or fold and a member having one end thereof received and clamped between said plait and the other end thereof normally in engagement with said bead, said member having a portion thereof spaced from the side of the box so that when pressure is applied thereto an initial relative longitudinal movement of the cover and body will be effected.

4. In a box comprising cover and body members one of which is provided with a bead and the other with an annular plait or fold, a member having one end received and clamped between said fold and the other end in engagement with said bead, said member having a portion thereof normally spaced from the side of the box so that when pressure is applied thereto an initial relative longitudinal movement of the members is effected.

5. The combination with a box including body and cover members one of which is provided with a bead, a normally curved resilient spring finger attached to the other member and engageable with the bead to effect

initial relative longitudinal movement of the members, of means for attaching the said finger to the other member comprising an annular plait in the member between the folds of which the spring finger is received and clamped.

6. The combination with a box including body and cover members one of which is provided with a bead, a normally curved resilient spring finger attached to the other member and engageable with the bead to effect initial relative longitudinal movement of the members, of means for attaching the said finger to the other member comprising an annular plait in the member between the folds of which the spring finger is received and clamped, the remainder of said plait constituting a peripheral bead or projection for manipulating the member to effect its entire separation from the other member.

7. In combination a box including a cover and a body having a bead thereon and means for opening the same comprising a bent spring member having one end thereof fixed to the cover and held against relative rotation with respect thereto, the other end of said member normally engaging the bead of said body, of means of attaching said spring member to the cover comprising an expanded plait or fold in the cover between which the same is clamped.

CLEN S. HUMPHREY.
